(57) **CLAIM**

The ornamental design for a pen container, as shown and described.

DESCRIPTION

FIG. 1 is a front elevation view of a pen container showing my new design;

FIG. 2 is a rear elevation view thereof;

FIG. 3 is a right side elevation view thereof, with the left side elevation view being a mirror image of the right side elevation view;

FIG. 4 is a top plan view thereof;

FIG. 5 is a bottom plan view thereof;

FIG. 6 is an upper front perspective view thereof; and,

FIG. 7 is an upper front exploded perspective view thereof. The broken lines shown in FIG. 5 illustrate environmental subject matter and form no part of the claimed design.
